Frank Ledermann

UNITED STATES PATENT OFFICE.

DAVID UMANOFF, OF NEW YORK, N. Y.

SPRING CLAMP FOR TELEPHONE INDEXES.

Application filed November 3, 1919. Serial No. 335,552.

To all whom it may concern:

Be it known that I, DAVID UMANOFF, citizen of the United States, residing at New York, in the county of New York and State 5 of New York, have invented certain new and useful Improvements in Spring Clamps for Telephone Indexes, of which the following is a specification.

This invention relates to spring clamps, 10 and has for its main object to provide a device which is simple in construction and operation, and inexpensive in cost of manufacture.

Another object of the invention is to provide such a spring clamp composed of one piece of resilient material such as metal wire, bent so as to provide a pair of resilient jaws and an eye-like projection for securing the clamp to a support.

Another object of the invention is to provide a clamp by means of which an index may be removably secured to a support, such as, for instance, the mouth-piece of a telephone.

The above and other objects will become apparent in the description below, in which like characters of reference refer to like-named parts on the accompanying drawing. The drawing illustrates the clamp applied 30 to a telephone index, the same being used to retain the index in position on and to prevent its accidental falling off from the mouth-piece of the telephone or sliding along its essentially conical surface.

Referring briefly to the drawing, Fig. 1 illustrates, in a front elevational view, the clamp applied to the mouth-piece of a telephone.

Fig. 2 is a side elevational view of the same.

Referring to the drawings, the numerals 1 and 2 indicate the arms of the clamp, which is constructed of resilient material by bending into the shape shown, the clamp 45 arms being suited to fit about the outer portion of the mouth piece 7.

A single coil 3 is formed in the top of the clamp which is adapted to pass through a hole 4 of the index backing plate or base 9, 50 when the clamp arms 1 and 2 are outwardly swung, thus reducing the diameter of the

coil 3. Thereupon the coil is inserted through the hole 4 and the arms are allowed to approach each other enlarging the diameter of the coil 3 and causing the same 55 to be securely retained on the back of the base plate 9.

The free ends of the arms 1 and 2 are provided with loops 5 and 6 adapted for contact between the face of the plate 9 and the back of the pad 8, and said pad is fixed to the plate 9 by means of eyelets 10, located at the corners only, whereby the pad 8 and plate 9 are sufficiently spaced apart to allow for swinging movement of the arms 65 1 and 2.

When the device is mounted on the mouthpiece 7, the arms 1 and 2 are slightly separated or swung apart to permit the clamp to pass over its front and then spring 70 inwardly, thus retaining the clamp on the mouthpiece, the plate 9 being provided with a hole 9^a, which is of greater diameter than the mouthpiece.

Having thus described my invention, what 75 I claim and desire to secure by Letters Patent is as follows:

1. In a device of the character described, an index plate having a relatively small aperture through its upper part and a larger 80 aperture adjacent thereto, and a clamp of resilient material comprising two arms and a normally expanded connecting coil which is extended through said small aperture, said arms adapted to clasp a telephone mouth-piece.

2. In a device of the character described, an index plate having a relatively small aperture through its upper part and a larger 85 aperture adjacent thereto, and a clamp of resilient material comprising two arms and a normally expanded connecting coil which is extended through said small aperture, said arms adapted to clasp a telephone mouthpiece, and a pad, and means for connecting the same to said plate, whereby the plate is sufficiently spaced from the pad to allow for swinging movement of the clamp arms.

In testimony whereof I affix my signature. 100

DAVID UMANOFF.
